POSTURE CHAIR

Walter F. Herold, Bridgeport, Conn., assignor to
 The Bassick Company, Bridgeport, Conn., a
 corporation of Connecticut

Application September 7, 1935, Serial No. 39,542
 Renewed December 23, 1938

9 Claims. (Cl. 155—157)

The present invention relates to an improvement in posture chairs, particularly of the type in which the chair back is tiltably supported and is adapted to be adjusted, both as to angularity and height, for the purpose of adapting the back to the particular person using the chair. An object of the invention is to provide a chair back supporting tilting element in the form of a unit structure which may be readily connected to the chair seat and in which adjustment means, for adjusting the tension, the angularity of the back, and the height of the back, are conveniently arranged so that they may be operated by the person while seated in the chair, in order to accurately dispose the back in the desired position. To this end the joint means of the preferred form of the invention consists of a hinged joint of rubber, the rubber being in the form of a tubular member disposed under permanent pressure between two coaxially movable members disposed one within the other and to each of which the rubber is in effect bonded or permanently secured, and the relative movement between these members being resiliently effected by the torsional strain set up in the compressed rubber.

Another object is to provide an adjustment means for adjusting the angularity of the chair back in which a cam is employed and is adapted to be operated by means of a hand screw, the arrangement being such that the adjustment may be effected with very little effort by the person seated in the chair. A further object is to provide height adjustment means which may be conveniently operated by the person seated in the chair and having cam means for releasing and securing the chair back in its adjusted position.

With the above and other objects in view an embodiment of the invention is shown in the accompanying drawings and this embodiment will be hereinafter more fully described with reference thereto, and the invention will be finally pointed out in the claims.

In the drawings:

Fig. 1 is a side elevation of a chair back tilting mechanism, according to the invention, the rearward portion of the spider arms of the chair seat to which the mechanism is secured being shown, and the upper portion of the chair back being broken away.

Fig. 2 is a forward end elevation of the tilting mechanism, the spider arms being shown in vertical section, and portions of the chair back being broken away.

Fig. 3 is a top plan view, portions being broken away.

Fig. 4 is a vertical sectional view taken along the line 4—4 of Fig. 1.

Fig. 5 is a fragmentary plan view of a modified form of mechanism for adjusting the angularity of the chair back.

Fig. 6 is a perspective view showing certain parts of the back support and back in separated relation.

Fig. 7 is a perspective view showing certain parts of the bracket member and joint element in separated relation.

Fig. 8 is a perspective view of the tension adjustment collar.

Fig. 9 is a perspective view of the angle adjusting link plate.

Fig. 10 is a perspective view of the angle adjusting block and screw members.

Fig. 11 is a side elevation of a complete chair embodying a tilttable chair back mechanism according to the invention.

Similar reference characters indicate corresponding parts throughout the several figures of the drawings.

Referring to the drawings and particularly to Fig. 11 thereof, the chair comprises a base 10 of any suitable form upon which there is swivelly mounted a post 11 to which a pair of angle iron spider arms 12—12 are secured by rivets 13, the chair seat 14 being secured upon these angle irons. According to the invention the tilttable chair back supporting mechanism is secured to the spider arms 12—12 at a point near the rearward ends thereof.

The tilttable chair back supporting mechanism comprises a bracket member consisting of side arms 15—15 connected by a transverse platform portion 16, a pair of spaced cylindrical bearing portions 17—17 being formed at the upper side of the bracket for receiving the joint member, as will presently more fully appear.

The joint element comprises an outer tubular member 18, an inner tubular member 19, and a cylindrical body of rubber 20 between them, this rubber body being highly compressed and confined between the members 18 and 19 and being in effect bonded to their surfaces so that upon relative rotary movement between the members 18 and 19 the rubber body is put under torsional strain. In practice the rubber body is bonded to the inner member 19, as by vulcanization, and is then forced into the outer member 18 under great pressure, its diameter prior to insertion being considerably greater than the interior diameter of the member 18, so that the rubber is thus highly compressed and is in effect bonded to the inner

5

55

surface of the member 18 by the great surface friction set up between them under compression.

- The ends of the inner tubular member 19 of the joint element project beyond the rubber member 20, as well as beyond the outer tubular member 18, and are provided with grooves 21 which are adapted to be interlockingly engaged with inwardly embossed vertically extending ribs 22-22 extending above and below the joint receiving apertures 23-23 respectively provided in the sides of the spider arms, a tie-bolt 24, headed at one end and screw threaded at the other end being engaged through the bore of the inner tubular joint member 19 and through the apertures 23-23 and having a nut 25 screwed upon its threaded end, this assembly rigidly connecting the spider arms to the joint member 19 and providing a supporting spacer or strut between the arms. The outer joint member 18 is engaged in the spaced cylindrical bearing portion 17-17 of the bracket for rotary movement for the purpose of adjusting the tension of the joint element as will presently more fully appear. Within the space between the bearing portions 17-17 a tension applying and adjustment lever 26 is disposed, its collar portion 27 being engaged upon the intermediate portion of the outer joint member 18 and secured thereto by a set screw 28 in the collar engaging a recess 29 in the member 18. An adjusting screw 30 having a hand wheel or nut 31 at its lower end is engaged in a threaded opening 32 provided in the forwardly projecting end of the platform portion 16 of the bracket and is adapted to bear at its upper end upon the lever 26. It will be obvious that by adjusting the screw 30 the outer joint member 18 is rotated with respect to the bracket and the inner joint member 19 and through the torsional strain imposed upon the rubber member 20 any initial tension may be set up in the latter, the greater the initial tension the more force required to tilt the bracket. As seen in Fig. 1 the tension of the rubber exerts rotary pressure upon the bracket in clockwise direction, the bracket being limited in its movement in this direction by means of a pair of stop shoulders 33-33 formed upon the respective sides 15-15 and which abut the lower edges of the spider arms 12-12. The tilting action of the bracket when force is applied to the chair back is in counter-clockwise direction and this movement is limited by means of a pair of stop shoulders 34-34 formed upon the side portions 15-15 in angular relation to the stop shoulders 33-33 and which abut the lower edges of the spider arms at the limit of the tilted position. By rotating the adjustment lever in counter-clockwise direction through adjustment of the screw 30 the initial tension in the rubber is increased so that greater force is required to tilt the bracket.
- The side portions 15-15 of the bracket project downwardly and rearwardly with respect to the joint element and hingedly support a back supporting member 35, this member being provided at its lower end with a pair of apertured bearing lugs 36-36 which are engaged by a pin 37 also engaged through bearing apertures 38-38 provided in the side portions 15-15 of the bracket.
- The platform portion 16 of the bracket is provided with a stud 39 disposed along its central longitudinal axis and projecting downwardly at the under side and which engages an inclined cam slot 40 provided in one end of a link plate 41, the other end of this link plate being engaged in the

space between a pair of spaced flanges 42 and 43 formed upon the back supporting member 35 immediately above the hinge axis, and being provided with an aperture 44 engaged by a pivot pin 45 inserted in the flanges 42 and 43. The engagement of the end of the link plate between the flanges 42 and 43 is relatively loose, as is also the engagement of the pin 45 with the aperture 44, the inner surfaces of the flanges being also outwardly flared, as at 46 and 47, to permit relative swinging movement of the back member with respect to the link plate. The link plate is provided between its ends with a downwardly projecting stud 48 which engages a transversely disposed slot 49 provided in an actuating block member 50 disposed beneath the link plate, this block member having a threaded passage 51 therethrough in which is engaged an adjustment screw 52 rotatably supported in the side portions 15-15 of the bracket, the side plate 20 15 at one side having an aperture 53 rotatably engaged by the shaft 52, and side plate 15 at the other side having a reduced diameter aperture 54 engaged by a reduced shouldered end portion 55 of the shaft headed over as at 56, and which secures the shaft against relative longitudinal movement while permitting it to be rotated. The shaft is provided upon its outer end with a hand wheel or nut 57. By rotating the shaft movement is imparted to the block member 30 longitudinally of the shaft, which in turn causes the link plate 41 to be swung about the pivot pin 45 and through the engagement of the stud 39 with the inclined cam slot 40 swinging movement is imparted to the back supporting member 35 with respect to the bracket member to thus adjust the angularity of the back.

In Fig. 5 there is shown a modified form of adjustment means in which the link bar 41^a is provided with a longitudinal slot 40^a engaged by the stud 39 and is provided intermediate its ends with a stud 48^a engaging an inclined slot 49^a provided in an actuating adjustment block 50^a mounted for longitudinal adjustment movement upon the adjustment screw shaft 52. In this case the inclined slot 49^a imparts longitudinal movement to the link bar as the block member 50^a is moved by the adjustment screw 52.

The back supporting member 35 is provided with a vertically disposed slot 58 surrounded at the forward side of the member by a slightly raised rib portion 59. At the rearward side of the member 35 there is provided a vertical channel 60 having inclined side walls and which is engaged by a rib 61 formed centrally of the lower cross-piece 62 of the back member. The rib 61 is in the form of two vertically separated sections and between these sections there is secured a block member 63 having a projecting stud 64 engaged through a hole 65 in the back member 62 and secured thereto by riveting over its end, as at 66.

The block member 63 projects forwardly through the slot 58 and is provided with a slot 67 engaged by a rod 68 of square cross-section, this rod being provided near its inner end with an inclined cam surface 69 which is engaged by a pin 70 inserted through the block member. Upon the outer end of the rod 68 there is provided a threaded extension 71 engaged by a hand nut 72 having an annular groove 73 in its hub portion. The back member 62 is provided with a projecting lug 74 having a square opening 75 therein in which the rod 68 is engaged and is also provided with a projecting lug 76 having a recess 77 there-

75

in which is engaged the recess portion 73 of the hand nut and which prevents longitudinal movement of the hand nut while permitting it to be rotated, rotation of the nut imparting longitudinal movement to the rod 68. The hand nut 72 is located at a convenient position at the end of the back member 62 so that it may be readily turned by the person while seated in the chair. By turning the nut 72 to draw the rod 68 to the right, as shown in Figs. 2 and 3, the inclined surface 69 through its engagement with the pin 78 draws the back member 62 into tight engagement with the back supporting member 35 and at the same time the rod 68 is tightly pressed against the raised surface of the rib 59 so that the back member is thus locked in position. By turning the nut 72 to draw the rod to the left the back is released and may be readily adjusted vertically with respect to the back supporting member 35.

The back member is provided along its upper edge with forwardly projecting flanges 78-78 at each side of the back supporting member 35 and which may be conveniently gripped by the person seated in the chair to raise or lower the back member. Upright supports 79-79 are secured to the back member 62, these supports being connected at their upper ends by a cross piece 80 upon which is mounted the upper back engaging pad portion 81 of the back.

30 I have illustrated and described a preferred and satisfactory embodiment of my invention, but it will be obvious that changes may be made therein, within the spirit and scope thereof, as defined in the appended claims.

25 Having thus described my invention what I claim and desire to secure by Letters Patent is:

1. In an adjustable back support for use in a chair having a seat element, a bracket member adapted to be secured to said seat element, an angularly adjustable back-supporting member hingedly connected to said bracket member, a link member pivotally connected at one end to said back supporting member, one of said link and bracket members having a slot and the other having a pin engaging said slot and providing an operative connection between them, an adjustable block member having a threaded hole, an adjustment screw carried by said bracket member transversely of said link member engaging said threaded hole of said block member adapted to be rotated to move said block member transversely of said link member, one of said block and link members having a slot and the other having a pin engaging said slot and providing an operative connection between them for imparting movement to said link member upon movement of said block member, one of said slots being diagonal to the direction of movement of said block member and the other slot being longitudinal of said link member whereby upon said movement of said block member said link member is moved longitudinally with respect to said bracket member to cause angular movement of said back supporting member.

65 2. In an adjustable back support for use in a chair having a seat element, a bracket member adapted to be secured to said seat element, an angularly adjustable back supporting member hingedly connected to said bracket member, a
70 link member pivotally connected at one end to said back supporting member, one of said link and bracket members having a slot and the other having a pin engaging said slot and providing an operative connection between them, an adjustable block member having a threaded hole,
75

an adjustment screw carried by said bracket member transversely of said link member engaging said threaded hole of said block member adapted to be rotated to move said block member transversely of said link member, one of said block and link members having a slot and the other having a pin engaging said slot and providing an operative connection between them for imparting movement to said link member upon movement of said block member, said slot forming part of said operative connection between said link and bracket members being diagonal to the direction of movement of said block member and the other slot being longitudinally of said link member whereby upon said movement said link member is moved longitudinally with respect to said bracket member to cause angular movement of said back supporting member.

3. In an adjustable back support for use in a chair having a seat element, a bracket member adapted to be secured to said seat element, an angularly adjustable back supporting member hingedly connected to said bracket member, a link member pivotally connected at one end to said back supporting member, one of said link and bracket members having a slot and the other having a pin engaging said slot and providing an operative connection between them, an adjustable block member having a threaded hole, an adjustment screw carried by said bracket member transversely of said link member engaging said threaded hole of said block member adapted to be rotated to move said block member transversely of said link member, one of said block and link members having a slot and the other having a pin engaging said slot and providing an operative connection between them for imparting movement to said link member upon movement of said block member, said slot forming part of said operative connection between said block and link members being diagonal to the direction of movement of said block member and the other slot being longitudinal of said link member whereby upon said movement said link member is moved longitudinally with respect to said bracket member to cause angular movement of said back supporting member.

4. In an adjustable chair back support for use in a chair having a seat element, a bracket member adapted to be secured to said seat element, an angularly adjustable back supporting member having a hinge connection to said bracket member for pivotal movement about a transverse horizontal axis, a manually rotatable adjustment screw carried by said bracket member in forwardly spaced relation to said hinge axis, an actuating member operatively connected to said adjustment screw and arranged to have movement transversely of said bracket member, a part movably mounted on said bracket member arranged to have planular movement in a generally lateral direction connected at one point to said back supporting member spaced from said hinge axis and adapted at said one point to have movement in a direction transversely of said hinge axis, connected at another point to said bracket member, and connected at a third point to said actuating member whereby transverse movement of said actuating member imparts planular movement to said part, said connections of said part with said bracket member and said actuating member being so constructed and arranged that said planular movement causes said connection

with said back supporting member to move in said direction transversely of said hinge axis.

5. In an adjustable chair back support for use in a chair having a seat element, a bracket member adapted to be secured to said seat element, an angularly adjustable back supporting member having a hinge connection to said bracket member for pivotal movement about a transverse horizontal axis, a manually rotatable adjustment screw carried by said bracket member in forwardly spaced relation to said hinge axis, an actuating member operatively connected to said adjustment screw and arranged to have movement transversely of said bracket member, a part movably mounted upon said bracket member arranged for planular movement in a generally lateral direction connected at one point to said back supporting member spaced from said hinge axis and adapted at said one point to have movement in a direction transversely of said hinge axis, connected at another point to said bracket member, and connected at a third point to said actuating member whereby transverse movement of said actuating member imparts planular movement to said part, said connections of said part with said bracket member and said actuating member being so constructed and arranged that said planular movement causes said connection with said back supporting member to move in said direction transversely of said hinge axis, at least one of said points constituting a pivot about which said part moves during adjustment.

6. In an adjustable chair back support for use in a chair having a seat element, a bracket member adapted to be secured to said seat element, an angularly adjustable back supporting member having a hinge connection to said bracket member for pivotal movement about a transverse horizontal axis, a manually rotatable adjustment screw journaled in said bracket member in forwardly spaced relation to said hinge axis, an actuating member having threaded engagement with the screw threads of said adjustment screw and arranged to have movement transversely of said bracket member and longitudinally of said adjustment screw, a part movably mounted upon said bracket member arranged for planular movement in a generally lateral direction connected at one point to said back supporting member spaced from said hinge axis and adapted at said one point to have movement in a direction transversely of said hinge axis, connected at another point to said bracket member, and connected at a third point to said actuating member whereby transverse movement of said actuating member imparts planular movement to said part, said connections of said part with said bracket member and said actuating member being so constructed and arranged that said planular movement causes said connection with said back supporting member to move in said direction transversely of said hinge axis.

7. In an adjustable chair back support for use in a chair having a seat element, a bracket member adapted to be secured to said seat element, an angularly adjustable back supporting member having a hinge connection to said bracket member for pivotal movement about a

transverse horizontal axis, a manually rotatable adjustment screw journaled in said bracket member in forwardly spaced relation to said hinge axis, an actuating member having threaded engagement with the screw threads of said adjustment screw and arranged to have movement transversely of said bracket member and longitudinally of said adjustment screw, a part movably mounted upon said bracket member arranged for planular movement in a generally lateral direction connected at one point to said back supporting member spaced from said hinge axis and adapted at said one point to have movement in a direction transversely of said hinge axis, connected at another point to said bracket member, and connected at a third point to said actuating member whereby transverse movement of said actuating member imparts planular movement to said part, said connections of said part with said bracket member and said actuating member being so constructed and arranged that said planular movement causes said connection with said back supporting member to move in said direction transversely of said hinge axis, the connection of said part with said actuating member adapted during adjustment to move transversely of the axis of said adjustment screw, said actuating member having a slot permitting such movement.

8. A chair iron comprising a bracket member, a back member pivoted to said bracket member on a substantially horizontal hinge axis, and means for adjusting the angular relation between said back member and bracket member comprising a part movably connected to said bracket member adapted to have rocking movement about an axis transverse to said hinge axis, a shaft journaled in said bracket member substantially parallel to said hinge axis, operative connections movable along said shaft between said shaft and part causing turning of said shaft to rock said part, operative connections from said part to said back member spaced from the hinge axis, cooperating with the connection of said part with said bracket member, the construction and arrangement of said operative connections causing rocking of said part to turn said back member on said hinge axis, and operating means secured to said shaft.

9. A chair iron comprising a bracket member, a back member pivoted to said bracket member about a horizontal hinge axis, a shaft journaled in said bracket member substantially parallel to said hinge axis, a threaded actuating member having threaded connection with said shaft and movable therealong, a part movably connected to said bracket member adapted to move about an axis transverse to said shaft and connected to said threaded actuating member, a non-rigid connection between said part and said back member eccentric to said hinge axis, and operating means fixed to said shaft spaced from said bracket member, the construction and arrangement of said connections of said part causing moving of said part to turn said back member on said hinge axis.

WALTER F. HEROLD.
